UNITED STATES PATENT OFFICE.

JOSEPH A. MURRAY, OF YORK, PENNSYLVANIA.

SHINGLE.

Application filed March 14, 1925. Serial No. 15,540.

To all whom it may concern:

Be it known that I, JOSEPH A. MURRAY, a citizen of the United States, residing at York, in the county of York and State of Pennsylvania, have invented certain new and useful Improvements in Shingles, of which the following is a specification, reference being had therein to the accompanying drawing.

10 My invention relates to new and useful improvements in shingles and more particularly to a composition shingle which is cut from a strip or sheet of felt or other fibrous material thoroughly coated with asphalt or other water proof material and suitably surfaced.

The principal object of the invention resides in forming the shingle with a projection on one side edge, intermediate the top and bottom edges, said projection allowing the proper spacing of the shingles when laid upon a roof, the projection engaging the edge of an adjacent shingle whereby to space the strips longitudinally and the bottom edge of the projection acting as a gauge for properly spacing the shingles vertically.

Another object of the invention resides in so forming the shingle that the portion thereof lying beyond one end of the projection is of greater width than the portion lying beyond the opposite end of the projection, this formation allowing the shingles to be reversed, if desired, to have exposed spaces, between the lower ends of the shingles, of different widths or allowing the shingles to be laid to provide the greatest possible bearing surface for the overlying shingles and allowing for variations in the spacing of the shingles.

40 Still another object resides in so forming the projection on one side edge of the shingle that the shingles may be cut from a strip or sheet in the manner as disclosed in my copending application executed of even date herewith whereby there will be no waste of material and all shingles will be of a similar formation whereby they may be stacked or packed for shipment.

With the above and other objects in view, which will appear as the description proceeds, my invention consists in the novel details of construction, and arrangement of parts, described in the following specification and illustrated in the accompanying drawings, and while I have illustrated and described the preferred embodiments of the

invention, as they now appear to me, it will be understood that such changes may be made as will fall within the scope of the appended claim.

60 In the drawings:

Fig. 1 is a perspective of my shingle.
Fig. 2 is a top plan showing a plurality of shingles laid in the formation in which they will appear upon a roof.

65 Fig. 3 is a view similar to Fig. 2 showing a slight variation in the laying or positioning of the shingles.

Fig. 4 is a section on the line 4—4 of Fig. 3 looking in the direction of the arrows, 70 and

Fig. 5 is a bottom edge view of Fig. 3.

Composition shingles of the character to which my invention relates are ordinarily cut, as has been stated, from a strip or sheet of the material and it can readily be appreciated that they should be of such a formation as to allow them to be cut without waste of material. My shingle is of such a construction as to allow for this. 80 At the same time by forming the projection on the side of the shingles as I do the shingle will be what may be termed a self-spacing shingle so that it may be laid upon a roof without the necessity of employing experienced help and may be reversed if desired.

85 In the drawings 1 indicates a composition shingle preferably formed of a base of felt or other fibrous material entirely coated with asphalt or other water proof material and suitably surfaced with grit or the like. The body has the normal top edge 2, normal bottom edge 3, and side edges 4 and 5, a projection 6 being formed on the side edge 95 5 intermediate the top and bottom edges 2 and 3. The projection 6 is preferably of a length equal to the distance between the normal bottom end 7 thereof and the normal bottom edge 3 of the shingle and the width 100 of that portion of the body lying between the upper end 8 of the projection and the top edge 2 is of greater width than that portion lying beyond the bottom edge 7 of the projection and the edge 3 of the 105 shingle. In other words the upper edge 8 of the projection 6 is of less width than the bottom edge 7 thereof.

110 The formation of the projection 6 on one side edge of the shingle allows the shingles to be laid as more particularly illustrated in Figs. 2 and 3 of the drawings. The longi-

tudinal edge of the projection will engage the side edge 4 of the adjacent shingle and thereby space the shingles longitudinally to provide the spaces 9 therebetween so that 5 the exposed portions of the shingles when laid will simulate the appearance of the usual wood or tile shingles. It will be understood that one row of shingles over-lies the next adjacent row and in order to 10 properly space the shingles vertically the bottom edge 3 of the over-lying row of shingles will be positioned in line with the lower end 7 of the bottom row of shingles. Thus the shingles are so formed that they 15 may very easily be spaced both longitudinally and vertically to form a roof which is neat in appearance and in which the shingles, of composite form, will simulate as has been stated, the ordinary roof of wood shingles 20 or tiles.

In Fig. 2 of the drawings I have illustrated the shingles as laid with the longitudinal edge of the projection positioned on the vertical center line of that shingle which it 25 over-laps whereas in Fig. 3 of the drawings I have illustrated the shingles laid with the longitudinal edge of the projection of the over-lying shingle positioned on one side of the vertical center line of that shingle which 30 it over-laps. By having the normal upper end of the shingle of greater width than the normal lower end thereof it will be appreciated that when the shingles are laid upon the roof that there will be less space between 35 the adjacent shingles at the top than at the bottom. This formation is of considerable advantage in laying the shingles as shown in Fig. 3 and a greater bearing surface will be provided for the over-lying shingles than 40 would be the case if a greater space was provided between the adjacent shingles. At the same time by having one end of the shingle of greater width than the other if

desired the shingles may be reversed to provide a less space between the shingles at 45 the exposed ends thereof. By providing the projection of a length equal to the length of the normally exposed portion of the shingle it will be seen that the bottom or lower end of the projection of an over-lying or overlapping shingle will normally be on the same horizontal line as the upper or top end of the projection of the underlying or overlapped shingle, this aiding in properly positioning or spacing the shingles when laying. 55

I wish it understood that I do not desire to be limited to the specific dimensions illustrated in the drawings and while I have illustrated the distance between the normal top edge 2 of the shingle and the end 8 of the projection as somewhat less than the distance between the normal bottom edge 3 and the end 7 of the projection that the distances between the ends of the projection 60 and the ends of the shingles may be varied to provide the desired exposure when the shingles are laid.

Having fully described my invention what I claim as new and desire to secure by 70 Letters Patent is:

A shingle of the character described comprising a body portion having one vertical edge straight and the other vertical edge formed with a projection extending therefrom intermediate the top and bottom edges, said projection having a straight outer edge and one end thereof extending inwardly of the body portion a greater distance than the opposite end whereby that portion of the body lying beyond one end of the projection will be of greater width than that portion lying beyond the opposite end. 75

In testimony whereof I hereunto affix my signature.

JOSEPH A. MURRAY.
